[57] CLAIM

The ornamental design for a mechanic's creeper, as
shown and described.

DESCRIPTION

FIG. 1 is a perspective view of a mechanic's creeper
showing my new design;

FIG. 2 is a reduced top plan view thereof;

FIG. 3 is a reduced right side elevational view thereof,
the left side elevational view being a mirror image of
that shown;

FIG. 4 is a reduced front elevational view thereof;

FIG. 5 is a reduced rear elevational view thereof; and

FIG. 6 is an enlarged fragmentary side elevational view
taken along the line 6—6 of FIG. 2.

FIG. 1

FIG. 4

FIG. 5

FIG. 3

FIG. 6

FIG. 2
